UNITED STATES PATENT OFFICE.

HENRY S. LOCKWOOD, OF SOUTH NORWALK, CONNECTICUT, ASSIGNOR TO THE LOCKWOOD MANUFACTURING COMPANY, OF SOUTH NORWALK, CONNECTICUT, A CORPORATION OF CONNECTICUT.

LATCH SPINDLE.

Application filed July 26, 1921. Serial No. 487,587.

To all whom it may concern:

Be it known that I, HENRY S. Lockwood, a citizen of the United States, residing at South Norwalk, county of Fairfield, State of Connecticut, have invented an Improvement in Latch Spindles, of which the following is a specification.

This invention relates to locks and particularly to swivel spindles therefor and has for an object to improve the stop means thereon to facilitate the location of the swivel part of the spindle in the center of the lock.

Another object of the invention is to provide a stop means for swivel spindles for locks, which will be simpler and much cheaper to manufacture than those now in use.

Referring to the accompanying drawings illustrating my invention—

Fig. 1 is a perspective view of the lock detached showing one end of my improved spindle in position.

Fig. 2 is a section on substantially line 2—2, Fig. 1.

Fig. 3 is a perspective view of the spindle detached; and

Fig. 4 is a transverse section on line 4—4, Fig. 2.

Numeral 10 represents the casing enclosing the bolt and latch operating means and 11 the face plate through which the bolt 12 and latch 13 operate. The lock is secured in position in a recess in the door by means of screws passing through the openings 14 in the face plate as is well known.

Mounted to turn independently of each other in openings in the casing 10 are the sleeves 15 and 16 provided with square openings extending therethrough adapted for the insertion of the square swiveled spindle comprising two sections 17 and 18. These two sections are connected at their inner ends in the usual manner by a threaded stud 19 on one of the sections as 17 and a tapped hole in the end of the other section 18 threaded onto the stud. This allows either spindle section to be turned independently of the other and to turn its particular sleeve to operate the latch from either side of the door or from the inner side only according to the manner in which the buttons 20 and 21 are set, as is well known, the knobs of course being secured

to the outer ends of the spindle sections, 55 in the usual manner by screws extending into the tapped holes 22.

In applying the spindle to the lock after it has been secured in the door it is desirable to have some means of indicating to 60 the carpenter the proper location of the spindle so that the swivel joint will be located between the two sleeves 15 and 16 to insure that one sleeve only is operated by a single section. This is usually indicated by 65 means of a stop pin or pins on the spindle, which is applied by drilling a hole through the spindle and then forcing the pin into this hole. This requires several operations and is, therefore, expensive, and, furthermore, as the stop is a separate element from 70 the spindle there is always the possibility that it may work loose and be lost.

In forming the stop according to my invention, however, I upset one or more, preferably two, lugs 23 from two diagonally opposite edges of the spindle. These are both formed at the same time with one stroke of the punch, and it will be obvious 75 the cost of manufacture will be very much less than the old form with a pin set in a hole in the spindle. Furthermore, these lugs are integral with the spindle and so there is no possibility of their working 80 loose, and because of their peculiar formation are much stronger than the usual pin employed and are much less liable to injury 85 and distortion in handling.

As the lugs are both formed at the same time and on opposite sides of the spindle 90 there is no tendency for the spindle to turn in the support under the action of the punch, so there is no necessity of means for clamping the spindle in the support. It 95 will be evident that this also greatly reduces the cost of manufacture, as the operation of clamping and unclamping each spindle would consume considerable time.

Having thus set forth the nature of my invention, what I claim is:

1. In combination, a movable latch, a latch spindle comprising two sections swiveled together, and an operative connection between one of the spindle sections and the latch, one of said sections being provided with one or more stops struck up therefrom and arranged to position the spindle relative to the said operative connection.

2. In combination, a movable latch, a latch spindle, and means connecting the spindle and latch for operating the latch, said spindle being provided with one or more stop lugs struck up therefrom and arranged to position the spindle relative to said connecting means.
3. In combination, a movable latch, a latch spindle, means connecting the spindle and latch whereby the latter may be operated, said spindle being provided with stop lugs struck laterally therefrom on opposite sides of its axis and from the same side of a plane passing through its axis, and said lugs being arranged to position the spindle relative to said operating means.
4. In combination, a movable latch, a latch spindle comprising swiveled sections, an operative connection from one of said sections to said latch, one of said sections being provided with stop lugs struck up therefrom on opposite sides of the axis and from the same side of a plane passing through its axis, said lugs being arranged to position the spindle relative to said operative connection.
5. In combination, a movable latch, a latch spindle substantially square in cross section and provided with a stop lug struck up therefrom at one of its longitudinal edges, an operative connection from the spindle to the latch whereby the latch may be operated, and said lug being arranged to position the spindle relative to the operative connection.
6. In combination, a movable latch, a latch spindle substantially square in cross section
- and provided with a plurality of stop lugs struck up therefrom at diagonally opposite longitudinal edges, and means connecting the spindle and latch whereby the latter may be operated, the lugs being arranged to position the spindle relative to the connecting means.
7. In combination, a movable latch, a latch spindle comprising swiveled sections substantially square in cross section, one of said sections being provided with stop lugs struck up therefrom on diagonally opposite longitudinal edges, an operative connection between one of said sections and the latch, and said lugs being arranged to position the spindle relative to said connection.
8. In combination, a movable latch, a latch spindle substantially square in cross section and provided with stop lugs struck up therefrom at diagonally opposite longitudinal edges and from the same side of a plane passing through these edges, an operative connection from the spindle to the latch, and said lugs being arranged to position the latch relative to said connection.
9. In combination, a movable latch, a latch spindle substantially square in cross section, means connecting the latch and spindle whereby the latch may be operated, and stop means for positioning the spindle relative to said operating means comprising one or more lugs struck up from the spindle and laterally from an edge of the spindle.

In testimony whereof I affix my signature.
HENRY S. LOCKWOOD.
